(57) **CLAIM**

The ornamental design for a composite T-shaped in-line dowell reinforced wood stud for buildings, as shown and described.

DESCRIPTION

FIG. 1 is a front perspective view showing my new design for a composite T-shaped in-line dowell reinforced wood stud for buildings;

FIG. 2 is a right side elevational view;

FIG. 3 is a front elevational view;

FIG. 4 is a left side elevational view;

FIG. 5 is a rear elevational view;

FIG. 6 is a top plan view; and,

FIG. 7 is a bottom plan view.

The composite T-shaped in-line dowell reinforced wood stud for buildings is shown with a symbolic break in its length. The appearance of any portion of the article between the break lines forms no part of the claimed design.
